THE NORRIS PETERS CO., PHOTO-LITHO., WASHINGTON, D. C.

UNITED STATES PATENT OFFICE.

ADOLF BELER, OF PITTSBURG, PENNSYLVANIA, ASSIGNOR OF TWO-FIFTHS TO FREDERIC HARTLEY, OF PITTSBURG, PENNSYLVANIA, AND CHARLES H. PARSONS, OF SHARON, PENNSYLVANIA.

GAS-BURNER.

SPECIFICATION forming part of Letters Patent No. 706,683, dated August 12, 1902.

Application filed January 31, 1902. Serial No. 92,081. (No model.)

To all whom it may concern:

Be it known that I, ADOLF BELER, a citizen of the United States, residing at Pittsburg, in the county of Allegheny and State of Pennsylvania, have invented a new and useful Gas-Burner, of which the following is a specification.

My invention is an improved gas-burner adapted for use for heating, cooking, and other purposes; and it consists in the peculiar construction and combination of devices hereinafter fully set forth and claimed.

The object of my invention is to effect improvements in the construction of the burner whereby air is thoroughly commingled with the gas before the latter reaches the flame, so that the combustion of the gas is promoted, and the same is caused to burn with a blue flame.

A further object of my invention is to provide means for regulating the intake of the air which is commingled with the gas, so that a due proportion of the air may become commingled with the gas to cause the latter to be entirely consumed.

A further object of my invention is to effect improvements in the construction of the flame-spreader.

In the accompanying drawings, Figure 1 is a perspective view of a gas-burner embodying my improvements. Fig. 2 is a vertical central sectional view of the same. Fig. 3 is a similar view showing the burner disposed in the heating-dome of an apparatus for heating a coil of water-pipes.

In the embodiment of my invention I provide a deflector 1, which is here shown as of inverted conical form, having the downwardly-converging sides 2 and provided at its upper side with a series of upstanding and outwardly-projecting lugs 3, which are appropriately spaced apart, so that openings 4 are formed above the upper side of the deflector between the said lugs. On the latter, and hence above the deflector, is secured a flame-spreader 5. The same is here shown as of annular form and V-shaped in cross-section, whereby the flame-spreader is formed with downwardly-converging sides 6, between

which is formed a trough 7. In practice the 50 said trough may be kept supplied with water to prevent the burner from becoming overheated. The flame-spreader is here shown as secured on the lugs 3 by means of screws 8; but the same may be secured on 55 the lugs by any other suitable means, if preferred. I further provide a casing 9. The upper portion of the same is flared outwardly and upwardly, as at 10, and the interior diameter thereof is slightly in excess of the 60 exterior diameter of the upper portion of the deflector. The latter is disposed in the upper portion of the casing 9, and a channel 11 is formed between the deflector and the flared upper portion of the casing, said channel communicating at its upper end with the outer air at a point below the flame-spreader. The lower portion of the casing 9 is here shown as of cylindrical form, as at 12. The deflector is disposed concentrically with reference to the 65 casing. At the lower portion of the casing are a series of air-inlet openings 13. A hood 14, which is here shown as of truncated conical form, is provided with a cylindrical portion 15, which fits and is adapted to slide vertically 70 on the lower cylindrical portion of the casing, the said hood being disposed over the air-in- take openings 13. Any suitable means may be provided to secure the hood on the casing and 75 permit of the vertical adjustment of the hood. 80 I here show the cylindrical portion 15 of the hood provided with vertical slots 16 and set-screws 17 in said slots and engaging threaded openings in the casing, said slots and set-screws serving to secure the hood on the cas- 85 ing and adapting the hood to be vertically adjusted, so that it may uncover the air-in- take openings 13 to any desired extent, and thus vary the effective areas of said openings, and hence regulate the quantity of air which 90 passes inwardly through said openings to the interior of the casing. As here shown, the casing is secured to a supporting base-plate 18. Any suitable means may, however, within the scope of my invention be employed to 95 support the casing and the other parts of the burner. The said base-plate is adapted to be placed in the fire-box or dome of a stove,

furnace, or heater to serve as a horizontal partition and prevent air other than such as passes through the burner from being admitted to the flame.

5 At the lower end of the casing 9 is an air-intake funnel 19, which closes the lower end of said casing, is open on its lower side, and has an upwardly-extending cylindrical portion 20, which is disposed concentrically in 10 the casing 9 and extends upwardly to within a suitable distance of the lower side of the deflector, the upper end of the cylindrical portion 20 of the intake-funnel being open. The said cylindrical portion 20 of the air-intake funnel forms a primary mixing-chamber. A gas-supply nozzle or tip 21 is disposed concentrically in the lower portion of the air-intake funnel. The deflector 1 is here 15 shown as supported and secured in position 20 on the upper side of the casing by bolts 22, which connect the lugs 3 to the base-plate 18.

In the operation of my improved burner the gas is commingled with air in the primary mixing-chamber 20 and passes upwardly and is deflected outwardly by the 25 lower sides of the deflector 1. As the commingled air and gas escape from the primary mixing-chamber into the upper portion of the cylindrical part 12 of the casing 9 an additional quantity of air, drawn in through the 30 air-intake openings 13, is supplied to the gas and commingled therewith, the space between the cylindrical portion 20 of the air-intake funnel and the cylindrical portion 12 35 of the casing forming a secondary mixing-chamber 23. The deflector causes the commingled air and gas to be spread laterally in a thin film as it passes upwardly through the channel 11 between the flared or inclined 40 parallel portions of the deflector and casing, hence effecting the complete blending and commingling of the air and gas in such manner as to form a highly-combustible mixture. The flame is in practice blue, indicating an 45 almost perfect combustion of the gas, and is by the downwardly-converging sides of the spreader 5 spread laterally and divided, so that the heating capacity thereof is increased.

In Fig. 3 of the drawings I show one of my 50 improved burners disposed in the fire-box or dome 25 of a heater in which a coil of water-pipes 26 is disposed above the burner, the latter being utilized for heating the water in the said coil. The flue or draft-pipe 27, which 55 leads from the upper portion of the dome or fire-box and through which the heated air passes, has its lower end surrounded by a deflector 28, which is located concentrically in the upper portion of the coil 26, is of cylindrical form, with its lower side closed and its 60 upper side open, and serves to increase the efficiency of the burner in heating the coils by reflecting the heat laterally and forming a tortuous flue 29 between the sides of the deflector and the flue or escape-pipe 27, thereby 65 retarding the escape of the heated air

from the interior of the combustion chamber or dome. My improved burner may, however, be used for other purposes and in other connections, and I do not therefore desire to 70 limit myself in this particular. Neither do I desire to limit myself to the precise construction and combination of devices herein shown and described, as it is evident that modifications may be made therein without 75 departing from the spirit of my invention.

The channel 11 while ample to conduct the commingled gas and air to the base of the flame, owing to its linear extent and its diminished width, prevents the flame from 80 reaching the mixing-chamber and causing imperfect combustion of the gas.

Having thus described my invention, I claim—

1. A burner of the class described having 85 a deflector and a narrow channel leading therefrom to the flame, a primary mixer open to the outer air and having its inner end disposed opposite the deflector, means to discharge a jet of gas against the deflector, 90 through the primary mixer, whereby the commingled gas and air will be disposed in a thin film on the surface of the deflector, and a secondary mixer, to admit air to the surface of the deflector, at a point between 95 the primary mixer and the intake of the channel, substantially as described.

2. In combination with an outer casing having a flared portion and a contracted tubular portion leading thereto, said tubular 100 portion having means to admit air; a deflector in said casing, disposed proximate to the flared portion and across the contracted portion thereof, a narrow channel being thereby formed between them; an air-intake 105 funnel disposed in the contracted portion of the casing, opposite the deflector and open at its outer end for the admission of air, and a gas tip or nozzle disposed to discharge a jet 110 through the air-intake funnel and directly against the deflector, the air-intake funnel forming a primary mixing-chamber, the space 115 between said funnel and the contracted tubular portion of the casing forming a secondary mixing-chamber, at the surface of the deflector, from which secondary mixing-chamber the mixed gas and air pass through the narrow channel to the flame, substantially as described.

3. In combination with an outer casing 120 having a flared portion and a contracted tubular portion leading thereto, said tubular portion having air-inlet openings and means to vary the effective area thereof; a deflector in said casing, disposed proximate to the 125 flared portion and across the contracted portion thereof, a narrow channel leading to the flame being thereby formed between them; an air-intake funnel, disposed in the contracted portion of the casing, opposite the 130 deflector, and open at its outer end for the admission of air, and a gas tip or nozzle dis-

posed to discharge a jet through the air-in-take funnel and directly against the said deflector, for the purpose set forth, substantially as described.

5 4. In a burner, a mixing-chamber, a deflector therein and spaced therefrom to form a narrow channel between said mixing-chamber and said deflector and an annular flame-spreader disposed above the said channel

and adapted to contain water, substantially as described.

In testimony that I claim the foregoing as my own I have hereto affixed my signature in the presence of two witnesses.

ADOLF BELER.
